Arthur J. Shaukis

BY

Victor J. Evans

ATTORNEY

UNITED STATES PATENT OFFICE.

ARTHUR J. SHAUKIS, OF HAVERHILL, MASSACHUSETTS.

PENHOLDER.

Application filed December 19, 1925. Serial No. 76,508.

This invention relates to improvements in pen holders, the general object being to provide a reduced portion upon the forward end of the pen staff for securing the inner end of the sleeve thereon which in turn is provided with an annular flange upon its forward periphery to retain a concaved disk thereon to prevent accumulation of ink or other writing fluid upon the staff whereby the writer's fingers will be free from discoloration.

Another object of my invention resides in the provision of a split sleeve positioned within the first mentioned sleeve to retain the inner end of a pen point therein while the outer surface of the first mentioned sleeve is built up by a wrapping or sleeve like portion of a suitable resilient material whereby no hard substance is exposed to the fingers and no ill effect will be experienced.

With the above and other objects in view, the invention further includes the following novel features and details of construction, to be hereinafter more fully described, illustrated in the accompanying drawings and pointed out in the appended claim.

In the drawing:—

Figure 1 is an elevation of my invention.

Figure 2 is a fragmentary longitudinal section taken therethrough.

Figure 3 is an end elevation of my invention.

Referring to the drawing in detail, wherein like characters of reference denote corresponding parts, the reference character 10 indicates a pen staff provided with a reduced portion 11 upon its forward end and upon which is secured the inner end of a sleeve 12. The forward end of the sleeve is provided with an outwardly extending annular flange 13 the purpose of which will be readily apparent. Received upon the sleeve 12 and abutting the flange or shoulder 13 is a concaved hexagon-shaped disk 14 held in such position through the instrumentality of a layer of wrapping of resilient material 15 upon the sleeve 12 extending from the shoulder formed by the reduced portion 11.

Fitted within the bore of the sleeve 12 is a split sleeve 16 having its inner end correspondingly secured and positioned upon the reduced portion 11 of the pen staff 10 in order that pen points such as indicated at 17 may be replaced and withdrawn without extracting the split sleeve which expands 55 against the bore of the sleeve 12 and firmly holds the shank of the pen point against displacement.

The invention consists of a novel form of pen holder combining the results and advantages of the pen holders now in use but in addition provides the concaved hexagon-shaped disk to eliminate the pen staff from being inserted too far within an ink well and to prevent accumulation of the writing fluid 65 upon the pen staff.

The invention is susceptible of various changes in its form, proportions and minor details of construction, and the right is herein reserved to make such changes as properly fall within the scope of the appended 70 claim.

Having thus described the invention, what is claimed is:—

A pen holder of the character described comprising a pen staff provided with a reduced portion upon one end, a sleeve mounted upon the reduced portion of the staff and projected an appreciable distance therefrom, an annular flange carried upon the forward end of the sleeve and extended outwardly therefrom, a concaved disk having a central opening, said disk being provided with an offset portion located circumferentially of said opening and adapted to lie flush with the inner side of the flange upon said sleeve, a layer of resilient material arranged upon the sleeve immediately behind the offset portion of the disk to provide a suitable gripping surface, and a split sleeve positioned within the first mentioned sleeve and tensioned against the bore thereof to provide a resilient locking means for a pen point therebetween.

In testimony whereof I affix my signature.
ARTHUR J. SHAUKIS.
